C. MERRITT.

INVISIBLE HINGE JOINT FOR WALL BEDS.

APPLICATION FILED MAY 16, 1912.

1,039,986.

Patented Oct. 1, 1912.

UNITED STATES PATENT OFFICE

CARL MERRITT, OF SAN FRANCISCO, CALIFORNIA, ASSIGNOR TO RUDGEAR-MERLE & CO., OF SAN FRANCISCO, CALIFORNIA, A CORPORATION OF CALIFORNIA.

INVISIBLE HINGE-JOINT FOR WALL-BEDS.

1,039,986.

Specification of Letters Patent. Patented Oct. 1, 1912.

Application filed May 16, 1912. Serial No. 697,628.

To all whom it may concern:

Be it known that I, CARL MERRITT, citizen of the United States, residing in the city and county of San Francisco and State 5 of California, have invented new and useful Improvements in Invisible Hinge-Joints for Wall-Beds, of which the following is a specification.

My invention relates to what may be 10 called an invisible joint for the frames of wall beds, and the like.

It consists of a two-part bed frame, the meeting ends of which abut smoothly, with a tongue fixed in one of the parts and extending into the other portion, which is slotted upon one side, said tongue being also slotted so that the other member of the bed frame having a pin passing through the slot in the tongue, may slide thereon. The 15 tongue is cut away in such shape that when the two are separated, the second member of the frame may be turned at right angles with the first. The parts are closable and locked together without the use of sleeves, 20 or other visible supplemental parts.

The invention consists of the parts and the combination and construction of parts as hereinafter more fully described and claimed, having reference to the accompanying drawings, in which—

Figure 1 is a view of the bed frame in its normal position. Fig. 2 shows the parts separated before being bent to an angle with each other. Fig. 3 shows the parts 35 separated and bent at right angles.

In the manufacture of wall beds, it is desirable to so construct the foot board that it is in its normal position when the bed is horizontal, and which may be provided 40 with a joint allowing a portion of it to turn into a vertical position when the bed is turned up to stand vertically; the horizontally turned portion serving to form a space between the main portion and the 45 wall against which the bed is turned, which serves to receive the mattress, bed clothes, etc., while the jointed extension hangs vertically.

In carrying out my invention I prefer to 50 make the exterior frame of the bed of tubular rods.

A and B represent tubular sections of a bed frame; these sections being of equal diameter and so cut that they abut smoothly 55 without offsets of any kind. In the lower

portion of the tube B, as here shown, I fix a tongue 2. This tongue is preferably provided with a base 3 fitting the interior of the tube B, and so constructed that it may be secured by pouring melted metal around 60 the reduced portion, and also by a pin passing through it and the tube B, as shown at 4. The upper portion 2 of the tongue is flattened and has a width a little greater than that of the upper portion A of the 65 tube. One edge of the part 2 will thus be slidable against the interior of the tube A, while the other projecting edge may slide in a slot 5, which is formed in the tube A for that purpose, as shown. 70

The tongue 2 has a slot 6 made in it, and this slot is slidable upon a pin 7 fixed in the part A at such a point that when the two portions of the tube are drawn apart to the limit allowed by the slot 6 and pin 7, the 75 part A may be turned at substantially right angles with the part B. In order to allow this, a corner of the tongue 2 is rounded or cut-away as at 8, on a radius about the pin 7, and this allows the tongue to turn within 80 the closed side of the part A while the opposite side fits into the slot or channel 5. That portion of the tongue which enters the slot is also notched, as shown at 9, and when the parts A and B are turned to stand at 85 right angles with each other, the notch 9 will fit against the upper part of the slot 5 of the tube A. This allows the tongue to be made of a sufficient width, so that while one edge of it slides within the tube A, the 90 opposite edge of the lower part extends out flush with the outer circumference of the tube, while that portion which is slidable within the tube is of a width equal to the width of the interior diameter thereof. 95

It will be seen that by this construction, when the parts A and B are in their normal closed position, only a line of division can be seen; it not being necessary to employ any collar, sleeve, or other part to hold them in place; the tongue extending into the tube A and holding the parts rigid, while the edge which projects into the slot closes this, so that it forms a complete, continuous tube. 100

In wall beds it is desirable that when the bed is in an upright position it shall occupy as little space as possible. This hinge allows the legs of the foot end to remain in a vertical position when the bed is in an upright position and if properly adjusted to the 105 110

frame of the bed they will be folded inside of it when the bed is upright.

Having thus described my invention, what I claim and desire to secure by Letters Patent is—

1. A joint for tubular frames, said joint including two abutting tubes, one of which has an open slot upon one end, a flat tongue fixed in the other tube extending into the slotted one, and slideable therein, said tongue having a slot, and a pin fixed in first-mentioned tube upon which it is movable, and the upper end of the tongue having a circular curvature on the radius of the pin.
15. 2. A joint for tubular frames, consisting of two tubes of equal diameter adapted to abut against each other, and one of said tubes having a slot formed in one end, a tongue fixed in the opposing tube, one portion of which tongue is slideable within the slotted tube, and the other portion having a width adapted to fit and close the slot, said tongue having a longitudinally central slot,

a pin passing through the slotted tube upon which the tongue is slideable, said tongue having a notch formed in its edge adapted to engage with the slot of the tube when the parts are turned at right angles with each other.

3. A hinge comprising a hollow member provided at one end with a slot, a pin in said member arranged transversely of said slot, a second member, an ear projecting from said member provided with a longitudinal slot engaging said pin, and a shoulder on said ear adapted to engage the outer surface of the hollow member directly below said slot and hold the two members at a given angle to each other.

In testimony whereof I have hereunto set my hand in the presence of two subscribing witnesses.

CARL MERRITT.
